COMPRESSED AIR CONDITIONING APPARATUS

Clyde C. Farmer, Pittsburgh, Pa., assignor to The Westinghouse Air Brake Company, Wilmerding, Pa., a corporation of Pennsylvania

Application April 27, 1939, Serial No. 270,286

12 Claims. (Cl. 257—3)

This invention relates to compressed air conditioning systems and more particularly to an improved apparatus for dehydrating and purifying air under pressure for use in air brake systems and the like.

The water vapor content of air which has been drawn from the atmosphere and compressed for use in a railway air brake system is usually relatively high, and must be reduced by precipitation from the air before it is supplied to the pipes leading to the brake controlling valve devices of the brake system, in order to prevent accumulation of water in the system in such quantities as might destroy the lubricant in the various valve mechanisms or result in frozen pipes during cold weather.

One object of my invention is to provide an improved apparatus adapted to be associated with the usual compressor and main reservoir equipment of a locomotive for cooling and dehydrating the compressed air, and including means for preventing the apparatus from becoming clogged or frozen during cold weather.

Another object of my invention is to provide a compressed air dehydrating apparatus adapted to be carried by a vehicle and comprising condenser means, means for injecting a solvent such as alcohol into the condenser to free it from ice or foreign matter, heating means for the condenser, and a control device operative when the condenser becomes clogged to effect initial operation of the injecting means and subsequent operation of the heating means, until the condenser is again conditioned to permit free flow of compressed air.

Other objects and advantages of the invention will be apparent in the following description thereof, taken in connection with the accompanying drawings, in which

Fig. 1 is a diagrammatic view of one form of compressed air conditioning apparatus constructed in accordance with the invention, the essential elements being shown in section;

Fig. 2 is a diagrammatic sectional view of a similar apparatus embodying the invention in another form;

Fig. 3 is an enlarged detail, fragmentary view of the cooling conduit shown in Fig. 2;

Fig. 4 is a diagrammatic sectional view of an apparatus of the above class constructed in accordance with still another form of the invention; and

Fig. 5 is a fragmentary sectional view, in enlarged detail, of the cooling coil shown in Fig. 4.

Apparatus shown in Fig. 1

The apparatus shown in Fig. 1 of the drawings is adapted to be carried on a locomotive, and comprises a steam driven compressor 10, main reservoirs 11 and 12, a cooling condenser assembly 13, a control device 14, a liquid pump 15, and the usual air brake equipment represented by a brake valve device 16.

The compressor 10 is of the well known Westinghouse type and is adapted to be operated by steam supplied by way of a steam pipe 20, for supplying air under pressure through a pipe 21 to the main reservoir 11.

Interposed between the main reservoir 11 and the reservoir 12 is a conduit 23, which has a coiled section 24 mounted in a chamber 25 that is formed within a body 26 of the condenser assembly 13. The body 26 is provided with an exterior insulating jacket 27, and has formed in the lowermost portion thereof an inlet opening 28 communicating with the atmosphere by way of a duct 29 which is preferably mounted on the locomotive at a point remote from any heat radiating surfaces thereof. An interior wall or lining 26a for the casing 26 having spiral corrugations or grooves is provided for facilitating circulation of air admitted to the chamber 25 through the duct and opening 28. Mounted in the upper portion of the condenser assembly 13 is a blower or fan 31, which, when supplied with electric current as hereinafter explained, is operative to draw the air through the chamber 25 and outwardly by way of a passage 32.

The main reservoir 12 is adapted to collect water condensed from compressed air passing thereto from the coiled section 24 of the conduit, and is provided with an automatic drain valve device 17 for discharging the condensate at intervals. The drain valve device 17 may be of any suitable type and as illustrated comprises a unit similar to that shown and described in the U. S. Patent 2,125,144 issued July 26, 1938, to B. S. Aikman. If desired, a heat insulating jacket 33 may be secured about the main reservoir 12 for preventing heat radiated from the boiler of the locomotive from warming the air under pressure contained within the reservoir.

The liquid pump 15 comprises a casing 36 having a bore 37 formed therein and communicating by way of a port 38 and valve chamber 39 with the conduit 23, and also connected through a valve chamber 40 and pipe 41 with a reservoir 42 containing a quantity of alcohol or the like. The reservoir may be mounted somewhat higher than

the plunger bore 37 to facilitate supply thereto of alcohol. A plunger 44 is slidably mounted in the bore 37 and is adapted to be actuated by a piston 45, which is normally held in the uppermost position, as shown, by the force of a coil spring 46, and which piston is adapted to be forced downwardly upon the supply of fluid under pressure to a chamber 47 formed within the casing.

10 A ball check valve 48 is disposed in the chamber 40 for preventing back flow of alcohol therefrom to the reservoir 42. A similar ball check valve 49, disposed in the chamber 39, is normally held in seated position under the force of a spring 50 for preventing back flow of alcohol or air under pressure from the conduit 23 to the bore 37. It will be understood that the alcohol reservoir 42 may be provided with a suitable vent, not shown, for permitting withdrawal of liquid therefrom.

15 The supply of air under pressure to the piston chamber 47 of pump 15 is controlled through the medium of a magnet valve device 53, which comprises a casing having a valve chamber 54 communicating by way of a pipe 23a with the conduit 23 and containing a valve 55 that is normally urged into seated position under the force of a spring 56, and which is adapted to be unseated upon energization of the usual magnet 20 for establishing communication from the valve chamber through a pipe 58 to the piston chamber 47 as hereinafter explained. A valve 57 connected to the valve 55 by means of a fluted stem is provided for normally maintaining communication from the pipe 58 to the atmosphere by 25 way of a vent port 59.

30 Electric current is supplied to the magnet valve device 53 and to the motor driven blower 31 through separate circuits controlled by a switch mechanism indicated generally at 62, which is 35 operatively associated with the control device 14 hereinafter described. The switch device 62 comprises spaced stationary members 63 and 64 having suitable bores within which are disposed the 40 ends of a plunger 65 carrying a suitably insulated contact member 66, which is adapted when the plunger is positioned as shown in the drawings to bridge a pair of contact elements 67, and when the plunger is moved backwardly under the 45 force of the spring 68, to bridge a similar pair of contact elements 69.

50 With the contact member 66 in engagement with the contact elements 67 as shown, a circuit is completed for energizing the motor of the blower device 31, which circuit includes a generator or other source of power 72, a conductor 73, the contact elements 67 and 66, a conductor 74, the blower device 31 and a return conductor 75 connected to the generator. When the contact member 66 is shifted to the other position the above traced circuit is broken and another circuit is established, leading from the generator 72 through the conductor 73, contact elements 69 and 66, a conductor 77, the magnet of the 55 valve device 53, and a conductor 78 connected to the return wire 75.

70 The control device 14 comprises a casing structure 80 having mounted therein a pair of flexible diaphragms 81 and 82, which are operatively connected by means of an intermediate follower member 83 disposed within a chamber 84 formed between the diaphragms and communicating with the atmosphere. The diaphragm 81 is subject to the pressure of air in a chamber 85 which 75 communicates with the pipe 23a leading to the con-

duit 23. The diaphragm 82 is similarly exposed to the pressure of air in a chamber 86 which communicates with a pipe 87 leading from the main reservoir 12 to an auxiliary receiving reservoir 88 and thence to the brake valve device 16 which 80 controls distribution of compressed air to the usual air brake system. A pair of oppositely extending levers 90 and 91 are pivotally mounted on pins 92 and 93, respectively, carried by the casing structure within the chamber 84. The 85 inner ends of the levers 90 and 91 are operatively connected to the follower member 83 by means of a pin 95. The outer end 96 of the lever 91 is adapted to engage the adjacent end of the plunger 65 of the switch device 62 when the lever and the associated parts of the control device are in 90 normal position as shown in the drawings, for thereby maintaining the contact member 66 secured to the plunger in engagement with the contact elements 67.

95 A coil spring 98 is interposed between the lower wall of the chamber 86 of the control device and a follower member 99 engaging the diaphragm 82 for maintaining both diaphragms, the follower member 83 and the levers 90 and 91 in the 100 normal position as illustrated. The follower member 99 has a central stem 101 which extends downwardly and through an aperture 102 formed in the casing structure 80, the lower end of the stem being operatively aligned with an element 103 normally urged upwardly into engagement with lugs 104 formed on the casing under the force of a coil spring 105. It will be apparent that downward movement of the connected diaphragms 81 and 82 and the associated follower elements will be initially resisted by the coil spring 98, and upon engagement of the stem 101 with the element 103, by the combined forces of the spring 98 and of the spring 105.

105 The lever 90 of the control device 14 is adapted to operate a steam valve device 108, which comprises a casing having a bore within which is mounted a valve key 109 having an operating arm 110, to which the outer end of lever 90 is connected by means of a pin 111 riding in a slot 112 formed in the arm. It will be noted that the terminal portion of the slot 112 is so aligned with respect to the pivot pin 92 of the lever 90 as to permit an initial movement thereof from the position shown before the pin 111 becomes effective 110 to operate the arm 110 for rotating the key 109, this preliminary movement of the elements of the control device 14 being sufficient to lift the end 96 of the other lever 91 out of engagement with the switch plunger 65 to permit operation 115 thereof by the spring 68, as hereinafter explained. The valve key 109 is adapted to be operated from the normal position illustrated in Fig. 1 to establish communication from the steam pipe 20 through a branch pipe 20a to the chamber 25 within the casing of the conductor assembly 13. If preferred, the pipe 20a may be connected to the steam exhaust port of the compressor 10.

120 In operation, assuming that the several devices of the apparatus shown in Fig. 1 are initially set 125 in the position illustrated, steam supplied in the usual manner through the supply pipe 20 effects operation of the compressor 10 to supply air under pressure through the pipe 21 to the main reservoir 11. From the reservoir 11 compressed 130 air flows through the conduit 23, and in flowing through the coiled portion 24 thereof is cooled substantially to atmospheric temperature by reason of absorption of heat of compression therefrom into the draft of cooling air, which is circulated through the chamber 25 of the condenser 135 140

assembly 13 by operation of the electric blower device 31, which is supplied with current through the circuit hereinbefore described. From the cooling coil 24, the compressed air, together with water precipitated therefrom, is carried to the main reservoir 12, from which the precipitate is automatically discharged from time to time by operation of the discharge valve device 17. The cool, dry compressed air is then supplied by way of pipe 87 to the auxiliary receiving reservoir 88 and to the usual communications in the brake valve device 16.

It will be understood that during this time, while the coiled section 24 of the cooling conduit 23 is adapted to permit free flow therethrough of air compressed by the compressor, the pressures of air in both main reservoirs 11 and 12 and the conduit will be substantially uniform, and that consequently the fluid pressures acting on the diaphragms 81 and 82 in the control device 14 are substantially equalized so that the spring 98 remains effective to hold the diaphragms, together with the follower member 83 and levers 90 and 91, in their uppermost position shown in Fig. 1.

During cold weather, however, as moisture is precipitated within the coiled section 24 of the cooling conduit 23, a coating of ice may gradually accumulate within the coil, and the resultant clogging thereof may so impede the flow of compressed air as to cause the pressure in the conduit 23 and in the upper chamber 85 of the control device to exceed the air pressure in the lower chamber 86 communicating with the outlet end of the cooling conduit.

As the pressure of air in the chamber 85 thus becomes greater than that of air in chamber 86, the associated diaphragms 81 and 82 are gradually forced downwardly against the pressure of the spring 98, while the pin 95 carried by the follower member 83 effects rotation of the lever 91 about the pin 93 for causing the end 96 thereof to release the plunger 65 of the switch device 62. The spring 68 thereupon becomes effective to shift the plunger 65 and the contact member 66 out of engagement with the contact elements 67 and into engagement with the contact elements 69, thus breaking the circuit for the electric blower device 31 and establishing the circuit for energizing the magnet valve device 53.

Upon energization of the magnet valve device 53, the valve elements 57 and 55 are shifted in their lowermost position, against the force of the spring 56, and air under pressure is then supplied by way of the conduit branch 23a, chamber 54, and the piston chamber 57 of the liquid pump 15. The piston 45 is thereby operated to move the plunger 44 downwardly in the bore 37, thus forcing therefrom the quantity of alcohol previously drawn into or supplied to the bore by gravity flow from the reservoir 42, the alcohol being discharged past the then unseated check valve 49 and chamber 39 into the fluid conduit 23 and thence to the coiled section 24 containing the deposit of ice.

If the stopping of circulation of cooling air through the chamber 25 of the condenser assembly 13 and the injection of alcohol into the coiled section 24 of the conduit, as just explained, are not immediately effective to melt the ice accumulation, the differential in the pressure of air in the inlet portion of the conduit 23, and consequently in the chamber 25 of the control device 14, further increases with respect to the air pressure in the chamber 86 communicating with the

outlet portion of the conduit, so that the diaphragms 81 and 82 and the associated follower members 83 and 91 are shifted further downwardly against the force of the spring 98, and upon engagement of the stem 101 with the elements 103, against the combined forces of the springs 98 and 105. The lever 90 is thereby turned about the pin 92 through an angle sufficient to effect cooperation of the pin 111 thereon with the arm 110 of the valve device 108, and the valve key 109 is then turned into open position to supply steam from the supply pipe 20 by way of the branch pipe 20a to the chamber 25 within the condenser assembly. Upon circulation of steam about the coiled section 24 of the cooling conduit, the deposit of ice therein is quickly melted so that air under pressure may again be supplied therethrough to the main reservoir 12 in the usual manner.

Upon restoration of air pressure in the chamber 86 of the control device 14 equal to that in the chamber 85, the diaphragms 82 and 81 are again shifted to their uppermost position by the spring 98, and the levers 90 and 91 are consequently operated to effect closing movement of the valve key 109 and return of the contact member 66 of the switch device 62 to the position shown in the drawing, so that the circuit through which current is supplied to the electric blower device 31 is again established. The magnet valve device 53 is at the same time deenergized, and upon movement of the valves 55 and 57 to their normal position for venting piston chamber 47 of the pump 15, the spring 46 becomes effective to lift the plunger 44 upwardly for again permitting alcohol to flow from the reservoir 42 to the bore 37.

Apparatus shown in Fig. 2

The invention is embodied in somewhat different form in the equipment shown in Fig. 2 of the drawings, which comprises, in association with the compressor 10, main reservoirs 11 and 12, and brake valve device 16, a condenser assembly 113, a fluid pressure responsive control device 114, a liquid pump 115 and a steam valve device 116.

The condenser assembly 113 is similar to the device 13 shown in Fig. 1, and comprises a cylindrical casing structure 120 having interior spirally arranged grooves formed therein and sheathed with an insulating cover 121. A chamber 122 is formed within the casing 120 and communicates with the atmosphere by way of an inlet passageway 123 and an outlet passageway 124. An electrically operated blower device 125 is mounted in the casing of the condenser assembly 113 adjacent the outlet passageway 124. A cooling coil 128 is mounted within the chamber 122 of the condenser assembly, and communicates by way of an inlet conduit 129 with the main reservoir 11 and by way of an outlet conduit 130 with the main reservoir 12. In the present embodiment of the invention, the cooling coil 128 is adapted to contain a steam tube 131 of relatively small diameter, through which tube steam may be supplied to free the cooling coil of ice, as hereinafter explained. As is best shown in Fig. 3 of the drawings, a pipe fitting 133 is interposed between each end of the cooling coil 128 and the adjacent conduit leading to one of the main reservoirs, such as a conduit 130. The pipe fitting comprises a body 132 provided with a neck portion 134 adapted to receive the steam tube 131 and a gasket 136, which is tightly fitted

within the neck portion by means of a packing gland 135.

The steam valve device 116 is adapted to control the supply of steam to the tube 131 and comprises a casing having a valve chamber 138 communication with the tube and containing a valve 139, which is normally held in seated position by the force of a spring 140 and is adapted to control communication from the steam supply pipe 20 by way of a pipe 20b and through the valve chamber to the tube 131. The steam valve 139 has a stem 141 connected to a piston 142 which is operative, upon an increase on the pressure of fluid supplied to a chamber 143 formed in the casing, to unseat the valve against the force of the spring 140. It will be understood that the pipe 20b may, if preferred, be supplied with steam discharged from the operating cylinder portion of the compressor 10.

The liquid pump 115 comprises a casing having mounted therein a piston 153 adapted to operate a plunger 146 that is slidably mounted in a bore 147 formed in the casing, which bore is adapted to be supplied with alcohol from a supply reservoir 128 communicating therewith by way of a passage 149. The plunger 146 is normally maintained in a retracted position with respect to the bore 147 under the force of a coil spring 151, and is adapted to be actuated, under the pressure of fluid supplied to a chamber 152 and acting on the piston 153, to move into the bore 147 for expelling alcohol therefrom through a passage 154 and past a ball check valve 155 to a pipe 156, which communicates by way of the conduit 129 with the cooling coil 128. A ball check valve 158 is interposed in the passage 149 for preventing back flow of alcohol from the bore 127 to the reservoir 128.

The control device 114 comprises a casing structure having mounted therein a pair of flexible diaphragms 160 and 161, which are operatively connected together by a follower member 162 that is disposed within a central chamber 163 formed between the diaphragms and communicating with the atmosphere by way of an opening 164. The outer face of the diaphragm 160 is subject to the pressure of air in a chamber 166 communicating by way of a pipe 167 with the inlet conduit 129. The face of the diaphragm 161 opposite that exposed to the chamber 163 is subject to the pressure of air in a chamber 169, which communicates through a pipe 170 with the outlet conduit 130.

Formed within the casing of the control device 114 intermediate the diaphragms 160 and 161 is a valve portion 172 having a valve chamber 173, which is connected with the pipe 167 and has mounted therein a relay valve 174 adapted to control communication from the valve chamber to a chamber 175, which in turn is connected by way of a pipe 176 to the piston chamber 143 of the steam valve device 116. The relay valve 174 is normally held in seated position as shown in the drawing by the force of the spring 178 disposed in the chamber 173, and is provided with a stem 179 extending into the chamber 163 and disposed in operative alignment with a plate 180 carried by the follower member 162. The stem 179 has formed on the outer end thereof a valve portion 181 which is adapted to close communication between the chamber 175 and the atmospheric chamber 163 when the follower plate 180 is moved into engagement with the stem for unseating the relay valve 174, as hereinafter explained.

The follower plate 180 is also operatively aligned with the stem 185 of a plunger 186, which is slidably mounted in a suitable bore in a portion 187 of the casing extending between the associated diaphragms, and which plunger is urged toward the follower plate under the force of a spring 188. Associated with the control device 114 is a switch 190, which is adapted to control operation of the electric blower device 125 and comprises a spring contact member 191 extending into the chamber 163 within the casing of the control device, and a similar contact member 192 having an insulated end portion engageable with the plunger 186, which is normally adapted to maintain the contact member 192 in engagement with the member 191, as shown in the drawing. When the switch 190 is thus closed, a circuit is established for supplying current to the blower device 125, comprising a battery 194, a conductor 195, the connected contact members 191 and 192, a conductor 196, the motor winding of the blower device 125, a grounded conductor 197 and a grounded battery connection 198.

The control device 114 further comprises a valve portion 200, having formed therein a valve chamber 201 containing a valve 202 which is adapted to control communication from the diaphragm chamber 169 by way of a bore 203, the valve chamber 201, and a pipe 204 to the piston chamber 152 of the liquid pump 115. The valve 202 is normally held in seated position as shown in Fig. 2 under the pressure of a coil spring 206, which is interposed between a cap member 207 secured to the casing and a slidably mounted follower member 208 mounted in a bore in the portion 200 and engaging the valve. The valve 202 has a fluted stem 209 slidably mounted in the bore 203 and extending into operative alignment with the head of a bolt 210 carried by the follower member 162 adjacent the diaphragm 161. With the member 208 in normal position, the piston chamber 153 of pump 115 is connected to the atmosphere by way of the pipe 204, a port 211 in the bore containing the member, and a passage 212 in the cap member 207.

It will be observed that, when the diaphragms 160 and 161 and follower member 162 are disposed in the normal position as shown in Fig. 2 of the drawings, the stem 179 is more widely spaced from the plate portion 180 of the follower member than is the stem 185 of the plunger 186, which is thus adapted to be actuated prior to operation of the valve 174 upon movement of the follower member by the diaphragm 160, as hereinafter explained. The fluted stem 209 of the valve 202 is likewise initially positioned so as to be engaged by the bolt 210 at substantially the same time as the stem 185 is engaged by the follower plate 180, the valve 202 being thus adapted for operation simultaneously with operation of the switch 190.

Operation of the apparatus under normal conditions will be understood from the explanation hereinbefore presented in connection with Fig. 1 of the drawings, it being apparent that air under pressure supplied by the compressor 10 to the main reservoir 11 is adapted to flow through the conduit 129 to the cooling coil 128, where the compressed air is cooled due to the draft of atmospheric air drawn through the chamber 122 by operation of the blower device 125, so that moisture carried with the air is condensed therefrom and is collected in the second main reservoir 12, from which the condensate is discharged by the automatic drain valve device 17.

If the cooling coil 128 becomes clogged with ice, however, the pressure of air in the outlet conduit 130 and main reservoir 12 is gradually reduced below that in the main reservoir 11 and inlet conduit 129, due to continued supply of compressed air to the fluid pressure brake system, and the pressure of air in the diaphragm chamber 166 communicating with the conduit 129 is consequently enabled to force the diaphragm 160, follower member 162 and diaphragm 161 to the right, as viewed in Fig. 2. During initial movement of the follower member the plate portion 180 thereof is brought into engagement with the stem 185 of the plunger 186, which is then moved against the force of the spring 188 to permit movement of the spring contact member 192 away from the contact member 191 for breaking the circuit through which current is normally supplied to the electric blower device 125. Circulation of air from the atmosphere through the chamber 122 of the condenser assembly is thus stopped. At the same time, the bolt 210 is brought into engagement with the stem 209 for unseating the valve 202 and moving the follower member 208 to close port 211 against the force of the spring 206, so that air under pressure is quickly supplied from the main reservoir 12 by way of the pipe 170, chamber 169, past the unseated valve and through chamber 201 and pipe 204 to the piston chamber 152 of the liquid pump 115. The piston 153 and plunger 146 are thereby actuated to force alcohol from the bore 147 through passage 154, past check valve 155 and through pipe 156 to the inlet conduit 129, from which the alcohol is supplied to the cooling coil 128.

If the cooling coil 128 still remains clogged with ice, further increase in the differential between the respective pressures of air from the inlet and outlet conduits 129 and 130 acting on the associated diaphragms 160 and 161 of the control device causes continued movement of the diaphragms and follower member 162 toward the right, as viewed in Fig. 2, until the plate portion 180 is brought into engagement with the stem 179 for unseating the valve 174. Air under pressure is then supplied from the main reservoir 11 by way of the conduit 129, pipe 167, valve chamber 173, past the unseated valve 174, and through the chamber 175 and pipe 176 to the piston chamber 143 of the steam valve device 116. The piston 142 is thereby operated to move the steam valve 139 away from its seat against the force of the spring 140, and the resultant supply of steam from the pipe 20 to the tube 131 mounted within the cooling coil 128 then effects complete melting of the ice in the coil, and restoration of the desired free flow of compressed air from the inlet conduit 129 through the cooling coil to the outlet conduit 130.

When the obstruction due to frozen condensate is thus removed from the cooling coil 128, continued supply of air under pressure by operation of the compressor 10 effects build up of substantially uniform pressures in the main reservoirs 11 and 12 and the associated communications of the system, and the corresponding equalization of the air pressures in the chambers 166 and 169 of the control device 114 permits movement of the diaphragms 160 and 161 and the follower member 162 to their normal positions as indicated in Fig. 2, while the springs 178 and 206 effect movement of the respective valves 174 and 202 to their seated positions. The spring 188 is at the same time rendered effective to return the plunger 186 to its

normal position, in which the spring contact element 192 is held in engagement with the contact member 191 for closing the circuit through which current is supplied to the blower device 125.

As the valve 202 is moved to its seat by the force of spring 206 acting against the plunger 208, the plunger uncovers the port 211 through which communication is established from the piston chamber 152 of the pump 115 to the atmospheric exhaust port 212, and air under pressure is thereby vented from the piston chamber for permitting return movement of the piston 153 and plunger 146, by the spring 151, to the normal position as shown in the drawing. As the plunger 146 is withdrawn from the bore 147, alcohol is again supplied from the reservoir 148 past the check valve 153 and through the passage 149 to the bore, and the pump is thus conditioned for subsequent operation.

Similarly, when the valve 174 is moved to seated position by the spring 178, the valve portion 181 of the stem 179 is unseated, and air under pressure is thereby vented to the atmosphere from the piston chamber 143 of the piston valve device 116 through the pipe 176 and chamber 175, past the valve portion 181, and through the chamber 163 and opening 164, and the spring 140 is thus rendered effective to return the steam valve 139 to seated position for cutting off supply of steam to the steam tube 131.

Apparatus shown in Fig. 4

A somewhat different form of the equipment just described is illustrated in Fig. 4 of the drawings, wherein it will be observed that the compressor 10, main reservoirs 11 and 12, liquid pump 115, steam valve device 116 and control device 114 are associated with a condenser assembly 213, which differs in construction from the condenser assemblies 13 and 113 shown in Figs. 1 and 2.

The condenser assembly 213 comprises a heat insulated casing having an apertured interior baffle wall 215 which has formed at the lower side thereof a chamber 217, and at the upper side a chamber 218 having an atmospheric air inlet passageway 219 and an outlet passageway 220 formed adjacent the blower device 125. Mounted within the casing of the condenser assembly 213 is a cooling coil comprising an upper section 222 disposed within the chamber 218 and having one end communicating with the inlet conduit 129, and a lower section 223 mounted in the chamber 217 and having the upper end thereof connected by means of a pipe fitting 225 with the adjacent end of the section 222 and the lower end thereof connected through a pipe fitting 226 with the outlet conduit 130.

The lower cooling coil section 223 has associated therewith a heat exchange mechanism, comprising an electrically operated refrigerating unit 230 adapted to circulate a cooling fluid through a tube 231 that is mounted within the section 223. As is best shown in Fig. 5 of the drawings, the pipe fitting 226 comprises a body having a neck portion 233 adapted to receive the tube 231 and a gasket 235, which is closely fitted thereto by means of a packing gland 234 having screw-threaded engagement with the neck portion. The other end of the cooling tube 231 is similarly held in place by the pipe fitting 225.

The heat exchange or refrigerating unit 230 may be of any suitable type, and is adapted to be operated by current supplied to the circuit controlled by the switch 190, the heat exchange unit

230 and the electric blower device 125 being connected in parallel. The circuit for the heat exchange mechanism 230 is also adapted to be controlled by a thermostatically operated switch of conventional type, indicated at 236, which is responsive to a predetermined minimum atmospheric temperature for cutting the mechanism out of operation, the complete circuit comprising the battery 194, switch 190, conductor 196, a branch conductor 237, the thermostatic switch 236, a conductor 238, the heat exchange mechanism, a grounded conductor 239 and the grounded battery terminal 198.

In operation, the condenser assembly 213 is adapted to effect cooling of the compressed air supplied by the compressor in two stages. Air under pressure delivered by the compressor 10 flows through the pipe 21, main reservoir 11, which in Fig. 4 is represented as a pair of connected units, and thence through the inlet conduit 129 to the first stage section 222 of the cooling coil, where the compressed air is initially cooled by the draft of atmospheric air drawn through the passageway 219, chamber 218 and passageway 220 by operation of the electric blower 125 in the usual manner, it being understood that the switch 190 is at this time held in closed position, as hereinbefore explained. As the compressed air flows from the section 222 of the cooling coil to the second stage section 223 thereof, it is further cooled due to absorption of the heat of compression by the cooling fluid circulating through the tube 231 passing through the section 233, assuming that the thermostatic switch 236 is closed as shown in the drawing. The cooled air under pressure, together with the condensate deposited within the cooling coil sections 222 and 223, then flows through the outlet conduit 130 to the main reservoir 12, from which air under pressure is supplied to the fluid pressure brake system as already explained.

During cold weather, the temperature responsive switch 236 automatically assumes circuit opening position, and the heat exchange mechanism 230 is thus rendered inoperative to circulate fluid through the tube 231. If the flow of compressed air through the cooling coil within the condenser assembly becomes restricted due to formation of ice, the control device 114 is adapted to operate in the manner hereinbefore described in connection with Fig. 2 in the drawings, to effect operation of the alcohol pump 115 while opening the circuit for the electric blower 125, and to effect subsequent operation of the steam valve device 116 to supply steam through a pipe 240 to the chamber 217 of the condenser assembly, and thence through the apertures in the baffle wall 215 to the chamber 218, thereby insuring melting of the ice formation within the cooling coils and reestablishment of the supply of compressed air to the main reservoir 12.

While one embodiment of the invention and several modifications thereof have been described, it is not my intention to limit my invention to that embodiment or otherwise than by the scope of the appended claims.

Having now described my invention, what I claim as new and desire to secure by Letters Patent, is:

70 1. Apparatus for cooling and dehydrating fluid compressed by a compressor for delivery to a main reservoir, including in combination, a cooling conduit through which fluid is supplied from the compressor to the main reservoir, blower means operable to force a cooling draft over said

conduit at one time, steam supply valve means operable to supply steam for heating said conduit at another time, force-feed mechanism operable to inject a quantity of anti-freeze compound into said conduit, and fluid pressure responsive means subject to the opposing pressures of fluid in the inflow and outflow portions of the conduit for selectively controlling operation of said blower means, steam valve means and force-feed mechanism.

2. Apparatus for cooling and dehydrating fluid compressed by a compressor for delivery to a main reservoir, including in combination, a cooling conduit through which fluid is supplied from the compressor to the main reservoir, blower means operable to force a cooling draft over said conduit at one time, steam supply valve means operable to supply steam for heating said conduit at another time, force-feed mechanism operable to inject a quantity of anti-freeze compound into said conduit, and fluid pressure responsive means subject to the opposing pressures of fluid in the inflow and outflow portions of said conduit and operative normally to maintain said blower means in operation, and operative upon a predetermined differential in said fluid pressures to effect operation of said steam valve means and force-feed mechanism.

3. Apparatus for cooling and dehydrating fluid compressed by a compressor for delivery to a main reservoir, including in combination, a cooling conduit through which fluid is supplied from the compressor to the main reservoir, blower means operable to force a cooling draft over said conduit at one time, steam supply valve means operable to supply steam for heating said conduit at another time, force-feed mechanism operable to inject a quantity of anti-freeze compound into said conduit, and fluid pressure responsive means subject to the opposing pressures of fluid in the inflow and outflow portions of said conduit and operative upon a predetermined differential in said fluid pressures first to stop operation of said blower means while initiating operation of said force-feed mechanism, and then to effect operation of said steam supply valve means.

4. Apparatus for cooling and dehydrating fluid compressed by a compressor for delivery to a main reservoir, including in combination, a cooling conduit through which fluid is supplied from the compressor to the main reservoir, blower means operable to force a cooling draft over said conduit at one time, steam supply valve means operable to supply steam for heating said conduit at another time, force-feed mechanism operable to inject a quantity of anti-freeze compound into said conduit, and fluid pressure responsive means subject to the opposing pressures of fluid in the inflow and outflow portions of said cooling conduit and operative upon a predetermined initial differential in said fluid pressures to stop operation of said blower means while initiating operation of said force-feed means, and upon continued build up of a greater pressure differential to effect operation of said steam valve means.

5. Apparatus adapted to be carried on a locomotive for cooling and dehydrating air compressed by a compressor for delivery to a pair of main reservoirs, including in combination, a cooling conduit interposed between said main reservoirs and having a coiled portion, a heat-insulating housing enclosing said coiled portion and having air inlet and outlet openings in opposite ends thereof, electric blower means in one of said

housing openings, fluid pressure operated steam supply means operable to inject steam into thermal contact with said coiled portion of the conduit, and a control device comprising a switch 5 normally closing the circuit for said blower means, a valve operable to supply fluid under pressure to said steam supply means, and a movable abutment operative upon a predetermined differential in the respective pressures of air in 10 the inlet and outlet ends of said coiled portion of the conduit first to open said switch and then to effect operation of said valve.

6. Apparatus adapted to be carried on a locomotive for cooling and dehydrating air compressed by a compressor for delivery to a pair of main reservoirs, comprising in combination, a cooling conduit interposed between said main reservoirs and having a coiled portion, a heat insulating housing enclosing said coiled portion, 15 electrically operated cooling means for said coiled portion of the conduit, fluid pressure responsive heating means for said coiled portion of the conduit, and a control device comprising a switch 20 normally closing the circuit for said electrically operated cooling means, a valve operable to supply fluid under pressure to said heating means, and a movable abutment operative upon a predetermined differential in the respective pressures of air in the inlet and outlet ends of said 25 coiled portion of the conduit first to open said switch and then to operate said valve.

7. Apparatus adapted to be carried on a locomotive for cooling and dehydrating air compressed by a compressor for delivery to a pair of main reservoirs, including in combination, a cooling conduit interposed between said main reservoirs and having a coiled portion, a heat insulating housing enclosing said coiled portion, electro-responsive cooling means for said portion 30 of the conduit within the housing, a fluid pressure actuated pump operable to inject alcohol or the like into said conduit, fluid pressure responsive heating means operable to apply heat to said portion of the conduit within the housing, and an automatic control mechanism comprising a normally closed switch controlling supply of fluid under pressure to said pump, normally seated valve means controlling supply of fluid under pressure to said pump, normally seated valve means controlling supply of fluid under pressure to said heating means, and common actuating means responsive to restriction in the flow of air through said conduit for effecting operation of said switch and both of said valve means in 45 sequence.

8. Apparatus adapted to be carried on a locomotive for cooling and dehydrating air compressed by a compressor for delivery to a pair of main reservoirs, including in combination, a cooling conduit interposed between and communicating with said main reservoirs, a heat insulating housing enclosing said cooling conduit, electroresponsive cooling means associated with said cooling conduit, a fluid pressure actuated pump operable to inject alcohol or the like into said conduit, fluid pressure responsive heating means operable to apply heat to said conduit within the housing, and an automatic control mechanism comprising a normally closed switch 50 controlling the circuit for said cooling means, normally seated valve means controlling supply of fluid under pressure to said pump, normally seated valve means controlling supply of fluid under pressure to said heating means, and a movable abutment subject to the opposing pressures

of air in the respective main reservoirs for selectively effecting operation of said switch and both of said valve means.

9. Apparatus adapted to be carried on a locomotive for cooling and dehydrating air compressed by a compressor for delivery to a main reservoir, including in combination, a cooling conduit through which compressed air may be supplied by said compressor to a main reservoir, a casing enclosing a portion of said cooling conduit, electro-responsive cooling means associated with said portion of the conduit within said casing, a fluid pressure actuated pump operable to inject alcohol or the like into said conduit, fluid pressure responsive heating means operable to supply heat to said portion of the conduit within the housing, and an automatic control mechanism comprising a switch for controlling the circuit for said cooling means, normally seated valve means controlling the supply of fluid under pressure to said pump, normally seated valve means controlling the supply of fluid under pressure to said heating means, and a pair of diaphragms having a normal position for maintaining said switch closed and movable therefrom, upon a predetermined reduction in the air pressure in the outlet end of said conduit with respect to the air pressure in the inlet end, for causing said switch to open the circuit while effecting sequential unseating of said two valve means. 30

10. A compressed air cooling and dehydrating equipment adapted to be carried on a locomotive in association with a compressor and main reservoir, comprising the combination of a cooling conduit interposed between the compressor and main reservoir, cooling apparatus normally operative to remove heat of compression from air in said conduit, a supply pump operable to inject alcohol or the like into said conduit, thawing apparatus operable to apply heat to said conduit, and a common control mechanism automatically operative in accordance with variations in the freedom of flow of compressed air through said conduit to effect operation of said cooling apparatus at one time and of said pump and thawing apparatus at other times. 40

11. A compressed air cooling and dehydrating equipment adapted to be carried on a locomotive in association with a compressor and main reservoir, comprising, in combination, a cooling conduit interposed between the compressor and main reservoir, a fluid pressure operated pump adapted to inject alcohol or the like into said conduit, a magnet valve device operable when energized to supply fluid under pressure to said pump, fluid pressure responsive thawing apparatus operable to apply heat to said conduit, and a common control mechanism including a switch normally disposed in a first position for closing the circuit for said cooling means and operable to a second position for opening that circuit while closing the circuit for said magnet valve, a normally closed relay valve operable to supply fluid under pressure to said thawing apparatus, and a movable abutment operatively related to said switch and relay valve and operative by a differential in the air pressures at opposite ends of said cooling conduit initially to effect movement of said switch to the second position and then to open said valve. 55

12. Apparatus for cooling and dehydrating fluid compressed by a compressor for delivery to a fluid pressure system, comprising a first stage condenser conduit, a second stage condenser conduit, said conduits being arranged in series for 60

conducting fluid under pressure from said compressor to said system, blower means for circulating atmospheric air in thermal contact with said first stage conduit, refrigerating means for further cooling fluid under pressure flowing through said second stage conduit, thermostatically controlled means operable when atmospheric temperature is low to stop operation of said refrigerating means, mechanism operable to inject

fluid solvent into said conduits and to apply heat thereto for freeing said conduit of clogging deposits, and control means responsive to restriction in flow of fluid under pressure through said conduits for stopping both said blower means and said refrigerating means while effecting operation of said mechanism. 5
